UNITED STATES PATENT OFFICE.

CASSIUS CLAY PALMER, OF NEW YORK, N. Y.

REFRIGERATOR-CAR.

SPECIFICATION forming part of Letters Patent No. 330,044, dated November 10, 1885.

Application filed May 13, 1885. Serial No. 165,292. (No model.)

To all whom it may concern:

Be it known that I, CASSIUS CLAY PALMER, of the city, county, and State of New York, have invented a new and useful Improvement 5 in Refrigerator-Cars, of which the following is a specification.

Heretofore cars for transporting perishable substances in warm weather have been cooled by receptacles of ice or a freezing-mixture 10 located at the top, ends, or sides of the car.

The primary object of my invention is the combination, with the car-body and the trucks, of an ice-receptacle placed beneath the car-body and interposed between the two trucks. 15 By this arrangement great economy of room is secured, and the weight of the freezing-mixture is placed at the lowest possible point, so as to produce greater steadiness in the running of the car and less wear, and so as to require less strength in the construction of the 20 body of the car.

Figure 1 represents a longitudinal section taken through the center of the car. Fig. 2 represents a transverse section taken through 25 the middle of the car.

A is the space in the car in which are placed the substances to be refrigerated upon hooks or shelves or other suitable supports.

B is a pipe or conduit with perforations, as 30 shown, which runs preferably along the roof of the car, and thence extends downward at one end and along under the floor until it communicates with the fan C. The arrangement of the pipe B which I have shown I 35 deem to be preferable; but any other arrangement may be employed which would take the air from the car-body at any desired point or points and convey it to the fan C.

D is a box suspended from the timbers of 40 the body of the car intermediate the two trucks. This box incloses the apparatus for holding the ice and conveying the air into proximity to it for the purpose of being cooled. The exit for the air from the fan-blower connects with one end of this box and with a pipe, E, which runs from one end of 45 this box to the other near its bottom. At the end of the box opposite to the fan-blower the pipe E empties into a vertical passage, F, 50 which connects with the chamber G between the floor of the compartment A and the top of the ice-box. The floor of the compartment

A above this chamber G is perforated, so that the air is distributed in escaping from the chamber G into the compartment A, as indicated by the arrows. The pipe E is preferably oblong in cross-section, as shown in Fig. 2, and the top of this pipe, which forms the resting place for the ice, is supported on stays or trusses e, so as to secure the strength necessary for sustaining the weight of the ice. 55

H is the compartment where the ice is placed through the doors h h, one on each side of the ice-box. This compartment H extends over the pipe E and down at its ends, as at h' 60 h', Fig. 2. When the ice-box is charged, the ice will extend over the top of the pipe e and down around its ends, as at h' h'; but the space l, below the pipe E, is preferably made of such a limited vertical height that the ice will not 65 enter it, but so that it will be entered by the meltings from the ice, which finally escape 70 through a trap, as at m.

n is an air-space at the end of the ice-chamber, which will serve to isolate it from the outside atmosphere. 75

The fan C is preferably placed and suspended nearly on a level with the axle of the car, as shown, so that comparatively slight strain is brought to bear upon the belt I by 80 the motions of the car. Whatever variations occur in the tension of this belt will be taken up by the idler-pulley K. The power for driving the belt I is obtained from a pulley secured to the axle of the car. 85

The size and form of the pipe E and the relationship between it and the ice-compartment H will be regulated as circumstances require; but I prefer a form of pipe E oblong in cross-section, like that shown in the drawings, because of the fact that a greater surface of air is presented to the cooling-surfaces of the pipe in passing through. The space l below the pipe E is also preferred to be low, so that the drippings of the ice or ice and salt will be 90 brought intimately unto contact with the bottom of the pipe E, and thus themselves will 95 serve as an additional cooling agent.

When the car is running, the rotation of the fan C will draw the air into the perforations of the pipe B at the top of the car, where the air is warmest, and down to the eye of the fan. From the fan the air is forced through the pipe E, where it is brought in contact with the cooling. 100

surfaces against which the ice and drippings lie. The air is then forced up into the chamber G, whence it is distributed at the bottom of the car.

5. What I claim as my invention, and desire to secure by Letters Patent, is—

In combination with a car-body, an ice-box suspended underneath intermediate the trucks and containing a chamber adapted for ice or a
10 freezing-mixture, with doors *h* located on each side, through which the ice or freezing-mixture

may be introduced above the air-flue without opening the car, and an air-flue crossing said chamber near the bottom thereof and connected at one end with a fan and air-pipes leading 15 into the car, and at the other end with air-pipes leading into the car, all substantially as described.

CASSIUS CLAY PALMER.
